KITCHEN DRAFTING TEMPLATE

John D. Lannon, Bridgeport, Conn.

Application June 17, 1958, Serial No. 51,398

Term of patent 7 years

(Cl. D52—1)

Fig. 2 is an edge elevational view thereof.

The side opposite to that shown in Fig. 1 of the drawing is plain and uninscribed in appearance.

I claim:

The ornamental design for a kitchen drafting template, as shown and described.
